Patented 1871

United States Patent Office.

JOHN ABENDROTH, OF NEW YORK, N. Y.

Design No. 4,810, dated April 18, 1871.

DESIGN FOR A COOKING-STOVE.

The Schedule referred to in these Letters Patent and making part of the same.

To all whom it may concern:

Be it known that I, JOHN ABENDROTH, of New York city, in the county and State of New York, have invented a new and original Design for Cooking-Stove; and I do hereby declare that the following is a full, clear, and exact description thereof, which will enable others skilled in the art to make and use the same, reference being had to the accompanying drawing forming part of this specification.

The drawing represents a perspective view of my new design for stove.

This invention relates to a new ornamental design to be affixed to the panels and doors of cooking-stoves

and ranges, and consists in the application thereto of the representation of a magnolia flower.

A in the drawing represents a cooking-stove of suitable form or size.

Into the panels of the doors or sides are placed *alto rilievo* representations, B B, of magnolia flowers, with appropriate foliage for setting them off.

I claim as my invention—

The design for a cooking-stove, as shown.

JNO. ABENDROTH.
